[57] CLAIM

The ornamental design for a portion of a lawnmower, as shown and described.

DESCRIPTION

FIG. 1 is a perspective view of a portion of a lawnmower showing my new design;

FIG. 2 is a top plan view thereof;

FIG. 3 is a front elevational view thereof;

FIG. 4 is a right side elevational view thereof, the left side view being a mirror image of that shown; and,

FIG. 5 is a rear elevational view thereof taken along line 5—5 in FIG. 4.

The present application is directed to the design illustrated in the drawings. Other features of the drawings that are not considered part of the design sought to be patented are shown in broken lines.

The bottom of the portion of the lawnmower illustrated is not visible in its normal or intended use. Therefore, the bottom view is not a matter of ornamental concern, and has been omitted from the drawings.
